UNITED STATES PATENT OFFICE.

FREDERICK M. ROSS AND HARRY L. COOK, OF CINCINNATI, OHIO.

DIRIGIBLE LAMP AND DIRECTION-INDICATOR.

1,223,737.

Specification of Letters Patent.

Patented Apr. 24, 1917.

Application filed April 5, 1916. Serial No. 89,188.

To all whom it may concern:

Be it known that we, FREDERICK M. Ross and HARRY L. COOK, citizens of the United States of America, and residents of Cincinnati, in the county of Hamilton and State of Ohio, have invented a new and useful Improvement in Dirigible Lamps and Direction-Indicators, of which the following is a specification.

10. This invention relates to improvements in dirigible lamp attachments and direction indicators for automobiles and particularly to a combined dirigible lamp attachment and direction indicator having for an object 15 the construction of a combined day and night direction signaling apparatus having simultaneous movement of the indicator and lamps, and in which one of the lamps moves with the direction indicator to indicate one direction of travel, the other lamp, and the indicator being movable in the opposite direction to indicate the opposite direction of travel.

20. A further object is to produce a combined direction indicator and lamp directing apparatus in which operation of the lamps and indicator may be secured either when the steering gear is operated or independent of the operation of the steering gear.

30. These and other objects are attained in the apparatus described in the following specification and illustrated in the accompanying drawings, in which;

Figure 1 is a fragmental plan view of the vehicle chassis, the front axle, front wheels, and steering gear, with a combined direction indicator and lamp directing device embodying our invention attached thereto.

40. Fig. 2 is a front elevation of the apparatus disclosed in Fig. 1.

Fig. 3 is a sectional view taken on the line 3-3 of Fig. 1.

Fig. 4 is a sectional view taken on the line 4-4 of Fig. 1.

45. Fig. 5 is a longitudinal section of a detail of our invention.

Fig. 6 is a sectional view taken on the line 6-6 of Fig. 5.

50. Fig. 7 is a vertical section of a lamp bracket or support embodying a detail of our invention.

Fig. 8 is a transverse sectional view taken on the line 8-8 of Fig. 7.

55. Fig. 9 is a rear view of an auxiliary direction indicator located at the rear of the vehicle chassis.

The combined direction indicator and dirigible lamp construction embodying our invention, consists of two rotatable lamp brackets 10 and 11 mounted in forwardly extending clamps 12 and 13 secured to posts 14 and 15 which are preferably portions of the original lamp bracket supports with which motor vehicles are provided. The clamps 12 and 13 are provided for the purpose of holding the apparatus for moving the lamps, beyond any portion of the vehicle which would interfere with their movement. Extending from each of the brackets 10 and 11 are arms 16 and 17 attached 65 respectively thereto, and connecting these arms is a device 18 which performs the function of permitting independent movement of the lamps, and of returning and retaining the lamps in their normal straight 70 ahead positions when the operating mechanism therefor is inoperative. Operation of the lamps is controlled by an arm 19 extending toward the rear of the vehicle and operatively connected with the reach rod 20 75 extending between the crank arms 21 and 22 of the steering knuckles 23 and 24. The arm at its forward end is secured to a pivot post 25 operatively mounted in a bracket 26 secured in a side extension 27 of the clamp 80 12. At the upper end of the shaft 25 a forwardly extending arm 28 is provided, the arm being connected with a reciprocating block 30 mounted in a tube or casing 31 forming the body of the device 18. At the 85 opposite side of the vehicle and forming a portion of the clamp 13 is an extension 32 constructed in the same manner as the extension 27 and provided with a bracket 33 in which is pivoted a shaft 34 which is 90 provided with a crank arm 35 connected in turn with hand levers 36 located adjacent to the steering wheel 37, by means of cables 38 and 39. At its upper end the shaft 34 95 is provided with a forwardly extending arm 40, which is connected by a link 41, with the under side of the tube or casing 31. Within the casing 31 is reciprocally mounted a tube 42, which is provided with a rod 43, extending 100 to a point adjacent to the forwardly extending arm 16 of the lamp bracket 10, and so constructed as to be connected therewith. The block 30 abuts the tube 42 so as to move the tube out of the casing 31, by operation 105 of the rearwardly extending arm 19, connected with the steering gear. This movement of the tube 42 and block 30 is re-

strained by the spring 44, located within the tube, and having its end in abutment with a screw threaded collar 45, located in the end of the tube 42. The opposite end of the 5 spring abuts the headed end 46 of a rod 47, extending into the casing 31, and through the block 30, the block being reciprocally mounted thereon. Movement of the rod 47 toward the lamp bracket 10 is effected when 10 the block 30 is moved toward the bracket to compress the spring 44, by means of a collar 48, secured to the rod 47 by means of a set screw 49, the collar engaging the closed end 50 of the casing 31, to prevent 15 such movement. It will thus be seen that movement of the block 30 and tube 42 to rotate the lamp bracket 10 and thus cause the lamp to assume the position shown in dotted lines in Fig. 2, will cause the spring 20 44 to become compressed, and to tend to return the tube 42 and the abutting block 30, as well as its connected mechanism, to their normal positions as shown in full lines in Figs. 1 and 2. Located within the casing 25 31 and in engagement with the opposite face of the block 30, is a collar 51, secured to the rod 47 by means of a set screw 52, and secured to the tube 42, in engagement with the opposite end of the casing 31 is a 30 collar 53, the collar being secured to the tube by means of a set screw 54. These collars will permit movement of the block and tube in the direction of the bracket 10, without 35 causing operation of the rod 47. However when the block 30 is moved in the opposite direction, to abut the collar 51, the rod 47 connected therewith is also moved, the collar 48 moving away from the closed end 40 of the casing 31, and the collar 53 being brought into engagement with the open end of the casing 31, by reason of the travel of the spring 44, in engagement with the screw threaded collar 45, located within the tube 42. It will be seen that when the block 45 30 is moved toward the lamp bracket 11, as just described, the rod 47 will be operated, the tube 42 will be prevented from being operated and that consequently the headed end 46 of the rod 47 will cause compression 50 of the spring 44, which will tend to return the lamp and parts affected thereby to their normal positions. In the above description it will be seen that only one lamp is operated at a time, and that the movement of the 55 lamp is from its normal position toward the side of the vehicle on which it is located as shown in dotted lines in Fig. 2, the return motion bringing the lamp back to its normal position. In order to prevent the lamp 60 moving beyond its normal position and in the opposite direction, the bracket 10 is provided with a pin 55, see Figs. 7 and 8, and the sleeve 56 to which the arms 57 and 58 for supporting the lamp, are connected, is 65 provided with a notch 59, see Figs. 2 and 7, so as to provide shoulders 60 and 61, against which the pin may abut when the sleeve 56 is rotated. Thus when the sleeve 56 is rotated in the direction indicated by dotted lines in Fig. 2, the shoulder 60 moves away from the pin 55, but upon return of the sleeve to its normal position, the shoulder 60 abuts the pin 55, thus preventing movement of the lamp beyond its normal position. The construction of the bracket 11 is similar in all respects to that of the bracket 10, and for this reason the same reference numerals have been applied thereto. Extending from one side to the other of the vehicle, and mounted in lugs 62 and 63, extending therefrom, is a 70 transversely extending bar 64, see Fig. 2. Extending upwardly from this bar is a lug 65, having a pin 66, secured thereto, and adapted to engage a slot 67 of a direction indicating arrow 68, pivotally mounted at 75 68 on a plate 69, see Fig. 1, located at the rear, and secured to the casing 31. Movement of the arrow is secured when the casing 31 is reciprocated by means of the handles 36, located on the steering column, 80 the link 41 connected with the casing, being operated by means of its connected elements 40, 34, 35, 38 and 39. Movement of the arrow is thus secured, in addition to movement of the lamp toward which the arrow 85 is caused to point. When the arrow is moved to the left, the casing being in engagement with the collar 53 causes the tube 42, and connected rod 43, to move the lamp 90 mounted on the bracket 10, to the position 100 shown in dotted lines in Fig. 2. When the levers on the steering column are moved in the opposite direction, the link 41 moves the casing 31 toward the lamp, located on the right hand side of the machine, as viewed in Fig. 2, and the arrow is caused to point in that direction. Whether moving to the left or to the right, the arrow slot 67 slides with 105 relation to the pin 66, engaging the slot and thus causes the arrow to tilt in the desired 110 direction.

In order that the driver of a vehicle approaching the rear of the vehicle equipped with our improved direction indicator, may be acquainted with the intended direction of travel thereof, we have located at the rear an arrow or suitable auxiliary indicator 115 pivotally mounted on the pin 71 and having an arm 72 extending therefrom, the arm in turn being connected with a three armed lever 73 by means of a link 74. Connected with the vertical arms of the lever 73 are the ends of two cables 75 and 76 extending from the front to the rear of the vehicle chassis, the cables being connected directly with the arms of the lever 73 secured to the lower end of the shaft 34, or in any other suitable manner connected with the operating levers 36 mounted on the steering column. With this arrow located at the rear 120 125 130

of the vehicle and connected in the manner above described, movement thereof will be in the same direction as that of the arrow 68 at the front of the vehicle and therefore vehicles approaching from the rear will be duly warned of the intended direction which the vehicle in front is to take. At each of the pivots for the brackets 10 and 11 and the brackets 26 and 33, we have provided yielding devices such as springs 77, see Fig. 2, located between the brackets, and suitable adjustment devices on the shafts located therein, for the purpose of taking up any lost motion, and for thus preventing rattling 15 of the movable portions of our improved construction. This eliminates the noise which would be occasioned upon wearing of the parts.

In addition to this feature of construction 20 we preferably locate ball bearings 78 at both the upper and lower ends of each of the brackets. This is for the purpose of permitting ease of movement of the parts as well as permitting ease of adjustment 25 thereof.

In order that the amount of movement of the lamps to one or the other side, may be controlled, we have provided means consisting of adjustment devices for regulating 30 the lengths of the arms 16, 17, 28 and 40 and consequently limiting the amount of movement of the casing 31 or block 30 controlled thereby. The means for accomplishing this consists in reciprocally mounting the arms 35 16, 17, 28 and 40 in their respective brackets 10, 11, 26 and 33, set screws 10^a, 11^a, 28^a and 34^a, see Figs. 1, 2, 3 and 4, being provided for securing these arms in their adjusted positions.

40 In operation:

With the vehicle equipped with an improved construction such as above described and disclosed in the drawings, operation of the mechanism embodying our invention 45 consists in two methods of control. The first method of control is employed particularly at night, the motion of the steering wheel in rounding curves, controlling only the motion of the lamps. This operation 50 consists in causing the arm 19 to rock from one side to the other when the reach rod 20 is moved. Moving the arm 19 toward the bracket 11 will cause the arm 28 to pull the link 29 and consequently the block 30 and 55 thus cause the tube 42 and the rod 43, to move the lamp, located on the bracket 10, through the agency of the arm 16. This movement is against the tension of the spring 44, which is held by the headed end 60 46 of the rod 47, against movement the rod 47 being prevented from movement toward the bracket 10 by reason of the engagement of one of the shoulders 60 or 61 of the notch 59, of the bracket 11, which prevents movement of the lamp mounted on this bracket,

to a position other than its straight ahead position. This causes the spring 44 to be compressed and thus tend to return the block 30, the tube 42 and the bracket 10, to their original positions. During this operation the arrow 68 has not been moved from its normal position as shown in Fig. 2, the lamp only having been moved. Upon moving the steering gear in the opposite direction the block 30 is brought against the collar 51. This forces the rod 47 toward the bracket 11, and consequently causes the head 46 to compress the spring 44, the tube 42 and its connections being held against movement toward the bracket 11, by reason of the notch 59 and the pin 55, as above explained. Movement of the rod 47 therefore causes the lamp, mounted on bracket 11, to be turned to indicate the opposite direction of travel, the spring 44 in this operation also tending to cause return of the parts to their normal positions. In fact, it is our intention to so proportion the parts that the spring is provided with sufficient power to return the front wheels to their normal straight ahead positions, thus producing a safety feature in the construction embodying our invention, the strength of the spring being sufficient to cause the wheels to return to their straight ahead positions should any portion of the steering gear become broken or otherwise inoperative. In both of these operations the casing 31 is held against movement by reason of its connection with the link 41 and its connected mechanism. Thus the arrows 68 100 and 70 are maintained in their straight ahead positions.

In the day time the device is controlled by means of the handles 36 mounted on the steering column, movement of the handles 105 causing the casing 31 to move in one direction or the other. When the casing is moved toward the bracket 10 the arrow 68 is tilted in that direction to indicate that the vehicle is to be turned toward the left when viewed from its front as shown in Fig. 2. This movement of the casing 31 brings the tube 42 into operation because of its engagement with the collar 53 attached thereto, and thus causes the lamp mounted on the bracket 10 110 to be moved in that direction. This movement of the lamp, in addition to that of the arrow, is additionally valuable, since it also indicates the intended direction of travel of the vehicle. When the levers 36 are moved 115 in the opposite direction the casing 31 is moved toward the bracket 11 and into engagement with the collar 48. This causes the rod 47 to turn the lamp on the bracket 11, in the direction opposite to that of the 120 movement previously described, as well as causing the arrow 68 to move in the opposite direction. Both of these movements cause compression of the spring 44, because of the abutment afforded by the head 46, during 130

the first movement, when the tube 42 is moved toward the left, and by the abutment of the screw threaded collar 45 when the head 46 is moved in the opposite direction. 5 This compression of the spring 44, when the arrow is moved in either direction, will cause return of the arrow to its normal position upon releasing the handles 36. Simultaneously with the operation of the arrow 68, the 10 arrow 70 located at the rear of the vehicle is operated because of its connection with the arm 35 by means of which the link 41, which operates the casing 31, is operated.

In installing the apparatus it may be 15 found that the lamps in their movement, conflict with other portions of the car. This may be objectionable and in order to prevent the engagement of the lamps or their brackets with such portions, such as mud guards, 20 the set screws 10^a, 11^a, 28^a and 34^a are loosened, and the arms 16, 17, 28 and 40 are adjusted to make them of the proper length to move the lamps within the limits available. After the arms are adjusted and the 25 set screws tightened the movement will be found to be correct without interference of the lamps with any portion of the vehicle.

Having thus described our invention, what we claim is:

30 1. A combined dirigible lamp and direction indicating device for automobiles, comprising a lamp bracket rotatively mounted on the vehicle chassis, means for rotating the bracket, a yielding device and a direction indicator operatively connected with the yielding device and adapted to be moved from its normal position to a position corresponding with that of the movement of the bracket, said yielding device being 35 adapted to return the bracket and the indicator to their normal straight ahead positions when the bracket rotating means is released.

2. In a combined dirigible lamp and direction indicating device for vehicles, the 45 combination of two lamp brackets adapted to move from their normal straight ahead positions to positions in which the lamp rays are projected to one side or the other side of the vehicle, each bracket having stops for limiting its inward movement, a yielding device operatively connected with the brackets, adapted to return both brackets to their 50 normal straight ahead positions and to permit outward movement of one bracket independently of the other bracket, a direction indicator operatively connected with the yielding device and adapted to operate in one direction when one of the brackets is 55 operated and in the opposite direction when the opposite bracket is operated, and means for simultaneously operating the direction indicator and either one of the brackets to

indicate the direction of travel of the vehicle.

3. In combination in a combined dirigible lamp and direction indicating device for automobiles, a lamp bracket rotatively mounted on the vehicle chassis, manually controlled means for rotating the bracket and 65 adapted to be operated either from the steering gear of the automobile or independently thereof to rotate the bracket in one direction, a yielding device located between the means and the bracket, adapted to rotate the bracket in the opposite direction when the means is released, a direction indicator operatively connected with the yielding device, and stops for limiting the movement of the bracket from its normal straight ahead position to its abnormal side direction indicating position.

4. A combined dirigible lamp and direction indicating device for automobiles, comprising a lamp bracket rotatively mounted 85 on the vehicle chassis, a manually controlled means for rotating the bracket, a yielding device located between the means and the bracket, adapted to rotate the bracket in the opposite direction when the means is released, and a direction indicator operatively 90 connected with the yielding device, said yielding device consisting of a spring, a rod operatively connected with one end of the spring and with the bracket, an abutment 95 for the opposite end of the spring, and a link operatively connecting the means and the spring-engaging end of the rod, whereby the spring will be compressed upon movement of the bracket to its abnormal position.

5. In a combined dirigible lamp and direction indicating device for vehicles, the combination of two lamp brackets adapted to be moved from their normal straight ahead positions to positions in which the lamp rays are projected to one side or the other side of the vehicle, each bracket having stops for limiting its movement in but one direction, 105 a yielding device operatively connected with the bracket and adapted to return both brackets to their normal straight ahead positions and to permit movement of one bracket independently of the other bracket, and manually controlled means for operating either of the brackets against the tension exerted by the yielding device, said yielding device consisting of a spring, a rod operatively connected with one end of the spring and with one of the brackets, a rod operatively connected with the other end of the spring and with the other bracket, and a block located adjacent to the spring and adapted to be operatively connected with one rod when moved in one direction and with 110 the other rod when moved in the opposite direction.

rection, each rod when inoperative forming an abutment for its end of the spring, whereby the spring will be compressed upon movement of the bracket from its normal to its abnormal position by said means.

6. In combination in a combined dirigible lamp and direction indicating device for automobiles, a lamp bracket rotatively mounted on the vehicle chassis, manually controlled means for rotating the bracket and adapted to be operated either from the steering gear of the automobile or independently thereof, a yielding device located between the means and the bracket, adapted to 15 rotate the bracket in the opposite direction when the means is released, and stops for limiting the movement of the bracket from its normal straight ahead position to its abnormal side direction indicating position, 20 said yielding device consisting of a spring, a rod operatively connected with one end of the spring and with the bracket, an abutment for the opposite end of the spring, and a link operatively connecting the means and 25 the spring engaging end of the rod, whereby the spring will be compressed upon movement of the bracket to its abnormal position.

7. In a dirigible lamp apparatus for automobiles, the combination of two lamp brackets adapted to be moved from their normal straight ahead positions to positions in which the lamp rays are projected to one side or the other side of the automobile, each bracket having a stop for limiting its movement, a yielding device operatively connected with the brackets and adapted to return both brackets to their normal straight ahead positions and to permit movement of one bracket independently of the other bracket, 30 and means for operating either one of the brackets, said yielding device consisting of a spring, a rod operatively connected with one end of the spring and with one of the brackets, a rod operatively connected with the 35 other end of the spring and with the other bracket, and a block located adjacent to the spring and adapted to be operatively connected with one rod when moved in one direction and with the other rod when moved 40

in the opposite direction, each rod when inoperative forming an abutment for its end of the spring, whereby the spring will be compressed upon movement of either bracket from its normal to its abnormal position.

8. In combination in a dirigible lamp apparatus for automobiles, a lamp bracket operatively mounted on the vehicle chassis, means for rotating the bracket and adapted to be operated either from the steering gear 55 of the automobile or independently thereof, a yielding device located between the means and the bracket, and stops for limiting the movement of the bracket from its normal straight ahead position to its abnormal side 60 position, said yielding device consisting of a spring, a rod operatively connected with one end of the spring and with the bracket, an abutment for the opposite end of the 65 spring, and a link operatively connecting the means and the spring-engaging end of the 70 rod, whereby the spring will be compressed upon movement of the bracket to its normal position.

9. A combined dirigible lamp and direction indicating device for automobiles, comprising a lamp bracket rotatively mounted on the vehicle chassis, manually controlled means for rotating the bracket the desired amount, a yielding device located between the means and the bracket, and a direction indicator operatively connected with the yielding device and adapted to be moved from its normal position to a position corresponding with that of the movement of the 80 bracket, said yielding device being adapted to return the bracket and the indicator to their normal straight ahead positions when the bracket rotating means is released.

In testimony whereof, we have hereunto 90 subscribed our names this 30th day of March, 1916.

FREDERICK M. ROSS.
HARRY L. COOK.
